UNITED STATES PATENT OFFICE.

MAX MEYER, OF GRAND RAPIDS, MICHIGAN, ASSIGNOR TO THE ROSE PATCH AND LABEL CO., OF GRAND RAPIDS, MICHIGAN.

LABEL-MAKING MACHINE.

1,251,081.

Specification of Letters Patent. Patented Dec. 25, 1917.

Application filed April 20, 1917. Serial No. 163,470.

To all whom it may concern:

Be it known that I, MAX MEYER, a citizen of the United States, residing at the city of Grand Rapids, in the county of Kent and State of Michigan, have invented certain new and useful Improvements in Label-Making Machines, of which the following is a specification.

This invention relates to improvements in label making machines.

My improvements relate particularly to label strip feeding means and are particularly designed by me for embodiment in label cutting and folding machines such as in the patent shown in M. Petrocchi, January 9, 1917, No. 1,211,489, although capable of embodiment in other relations.

The main objects of this invention are:

First, to provide an improved feeding means for label making machines.

Second, to provide an improved feeding and tensioning means for label making machines.

Further objects, and objects relating to structural details, will definitely appear from the detailed description to follow.

I accomplish the objects of my invention by devices and means described in the following specification. The invention is clearly defined and pointed out in the claims.

A structure which is a preferred embodiment of my invention is clearly illustrated in the accompanying drawing forming a part of this specification, in which:

Figure I is a detail plan view of a structure embodying the features of my invention, only such parts of a label making machine being illustrated as I deem necessary to show an embodiment of my invention.

Fig. II is an enlarged detail section through the tension means for the label strip, taken on the line 2—2 of Figs. I and III.

Fig. III is a detail section of the tensioning means on a line corresponding to line 3—3 of Fig. II.

Fig. IV is an enlarged detail section through the feed taken on the line 4—4 of Fig. I.

Fig. V is an enlarged detail section of the

feed jaw on a line corresponding to line 5—5 of Fig. I.

In the drawing, similar reference characters refer to similar parts throughout the several views, and the sectional views are taken looking in the direction of the little arrows at the ends of the section lines.

Referring to the drawing, 1 designates the frame of the machine upon which is a slide-way 2 for the jaw slide or carriage 3. This jaw slide is, in the embodiment illustrated, in the form of a plate. A slot 5 is formed in the slide-way 2 to receive the slide block 6 which is adjustably secured to the slide by means of the screws 7, the slide having a longitudinal slot 8 therein through which these screws are disposed. The slide block 6 has a notch 9 in its lower end which is engaged by the anti-friction roll 10 of the actuating lever 11. On the slide 3 is a bracket 12 having an upturned flange 13 at one edge providing a jaw pivot ear and an upturned flange or jaw pivot ear 14 at its opposite edge. The jaw member 15 provided with downturned pivot ears 16 at its edges is mounted upon pivot ears of the plate 12 by means of the pivots 16'. The jaw member has a downwardly and forwardly projecting jaw proper 17 provided with teeth 17' adapted to engage the label strip 18 which is disposed under the jaw between the pivot ears of the plate 12.

The jaw has a rearwardly and laterally projecting arm 19 which is engaged by the spring 20. A stud 21 on the under side of the arm 19 holds the spring in place with the lower end of the spring resting upon the jaw slide. The jaw is also provided with the forwardly projecting stop arm 22 through which the stop 23 is threaded to engage the slide as shown in Fig V, whereby the teeth 17' can be adjusted to slide over the label but engage the stitching 26 to advance the strip.

A lock nut 24 locks the stop in its adjusted position. The spring urges the jaw into engagement with the label strip while the stop limits the closing movement of the jaw preventing such excessive pressure of the jaw upon the label as might injure the

label, as the label indicia are frequently affixed by stitching.

To insure an effective feed of the label strip it is provided with transverse rows of the stitching 26 which divide it into label lengths. The jaw is adapted to engage these transverse rows of stitching, thus insuring feeding of the label without the necessity of having the jaw engage deeply the fabric 10 of the label.

I preferably provide in this connection a tensioning device comprising the spindle 27 having a head 28 at one end, carrying spool spindles 29 disposed on opposite sides of the 15 axis of the spindle. Spools 30 are arranged on these spindles 29 and the tape is looped over both spools, that is, it is formed into bights, the bights being passed over the spools as clearly shown in Fig. II. The 20 spindle 27 is carried on a bracket 31 and is held under tension by means of the coiled spring 32, one end of which is engaged with the bracket at 33 and the other with the outer end of the casing 34 which is threaded 25 upon the spindle and secured in its adjusted position by the lock nut 35. A sleeve 36 is arranged on the spindle to support the spring. As the feed jaw reciprocates the labels are fed to the holding jaws designated generally by the numeral 37, and drawn through the folding jaws designated 30 generally by the numeral 38. Numeral 39 designates the cutter.

In operation, when the slide block 6 is urged forward by the lever 11 the teeth 17 engage with one of the transverse rows 26 of stitching and carry the label strip forward a distance equal to the length of a label, this being the throw of the block 6. 40 The end of the label strip is then grasped by the jaws 37 and the lever 11 then reverses its direction of movement carrying the block 6 and the jaw 17 rearwardly. The teeth 17' slide over the stitching forming 45 the name or indicia upon the strip and stop immediately behind the rows of stitching 26. The label is then severed from the end of the strip and the operation repeated. The tension device, due to the coiled spring 32, 50 maintains a yielding tension upon the strip as it is drawn forward by the jaw 17 and teeth 17'.

As the details of the jaws 37 and 38 and the cutter 39 form no part of my present invention I do not illustrate or describe the same herein. The same may be, however, an embodiment of the said patent to Petrocchi, No. 1,211,489.

I have illustrated and described my improvements in the form in which I have embodied the same in a machine such as shown in said patent. I have not attempted to illustrate or describe various modifications and other adaptations which might be desir-

able for other applications of my improvements as I believe the disclosure made will enable those skilled in the art to which my invention relates to embody or adapt the same as may be desired.

Having thus described my invention, what I claim as new and desire to secure by Letters Patent, is:

1. In a label making machine, means for feeding a label strip having transverse stitchings dividing it into label lengths comprising the combination of a reciprocating jaw slide, a supporting plate carried by said slide and having upturned pivot ears at its edges, said strip being arranged between said ears, a jaw member having downturned ears pivotally mounted on said supporting plate ears, and provided with a forwardly projecting jaw for engaging with the transverse rows of stitching of said label strip and forwardly, rearwardly, and laterally 85 projecting arms, an adjustable stop on said forwardly projecting arm, a coiled spring mounted on said slide to engage said rearwardly projecting arm, and means for reciprocating said supporting plate. 90

2. In a label making machine, the combination of a reciprocating jaw slide, a supporting plate carried by said slide and having upturned pivot ears at its edges, said strip being arranged between said ears, a jaw member having downturned ears pivotally mounted on said supporting plate ears, and provided with a forwardly projecting jaw and forwardly, rearwardly, and laterally 100 projecting arms, an adjustable stop on said forwardly projecting arm, a coiled spring mounted on said slide to engage said rearwardly projecting arm, and means for reciprocating said supporting plate. 95

3. In a label making machine, means for feeding a label strip having transverse stitchings dividing it into label lengths comprising the combination of a reciprocating jaw slide, a jaw member pivotally mounted on said slide and provided with a forwardly 105 projecting jaw, for engaging with the transverse rows of stitching of said label strip, and with forwardly and rearwardly projecting arms, an adjustable stop on said forwardly projecting arm, a spring mounted 110 on said slide to engage said rearwardly projecting arm, and means for reciprocating said slide. 115

4. In a label making machine, the combination of a reciprocating jaw slide, a jaw member pivotally mounted on said slide and provided with a forwardly projecting jaw and forwardly and rearwardly 120 projecting arms, an adjustable stop on said forwardly projecting arm, a spring mounted on said slide to engage said rearwardly projecting arm, and means for reciprocating said slide. 125

5. In a label making machine, means for

feeding a label strip having transverse stitchings dividing it into label lengths comprising the combination of a reciprocating jaw slide, a jaw pivotally mounted on said slide and adapted to engage with the transverse rows of stitchings of said label strip, a spring urging said jaw to its engaging position, an adjustable stop for said jaw, a spring mounted on said slide to engage said

rearwardly projecting arm, and means for reciprocating said slide.

In witness whereof, I have hereunto set my hand and seal in the presence of two witnesses.

MAX MEYER. [L. s.]
